UNITED STATES PATENT OFFICE

ROBERT KNOX, OF TORONTO, ONTARIO, CANADA

GLOVE DRIER

Application filed June 3, 1927. Serial No. 196,189.

This invention relates to a drier for hand coverings.

It is an object of the invention to provide a device of this character by means of which 5 gloves may be effectively dried without shrinkage, and which may be cheaply and ruggedly manufactured.

A further object of the invention is that of providing a glove drier which may be readily 10 stored, or, in use, properly suspended from a suitable support.

Reference is had to the attached sheet of drawings illustrating several embodiments of the present invention, in which:

15 Figure 1 is a plan view of a glove drier embodying the improved construction of the present invention; and

Fig. 2 shows an optional form of glove drier.

20 In these views the numeral 5 indicates the body of the drier which may be of any suitable material, preferably wood, and the lower end of which terminates in finger portions 6 to be inserted one within each of the fingers 25 of a glove; these portions being sufficiently spaced from each other so that air may freely circulate between the adjacent glove fingers.

It will be noted that the fingers are arranged so as to provide in aggregate what 30 might be termed a wedge, and the drier body, immediately to the rear of the finger portion, is rounded as at 7. Thus the drier is readily insertable into a glove, the arrangement of the fingers serving to distend the wrist and 35 body portions thereof, and the curved edges of the hand portion serving, as the glove is slipped into place on the drier, to retain the same snugly with the parts thereof distended. The body of the drier may be formed with 40 a series of perforations as at 8 so as to provide for the passage of air through the glove body.

With a view to supporting the drier the upper end thereof is formed with a slot, 45 which, as in Fig. 1, may extend inwardly as at 9 and terminate in an upwardly-extending portion 10, this slot being curved throughout its entire length. In Fig. 2 an angular slot 50 has been illustrated, terminating in an upwardly-projecting portion 11. In each of

these views it will be apparent that a suitable supporting member may be positioned, as has been indicated in dotted lines, in order to suspend the drier therefrom, detachment of the latter from the suspending element 55 being readily effected.

By means of a device embodying this invention a most efficient drier is provided for gloves of woven texture without danger of the latter shrinking during the drying operation.

The device may be readily suspended from a supporting member while the glove is drying, and detached therefrom. In this connection it will be appreciated that, due to 60 avoiding use of a metal eyelet or similar structure for suspending the drier, the danger of rust spots is eliminated; and, furthermore, when the drier is not in use a number of them may be stacked in compact form, preventing danger of warping.

Thus, among others, the several objects specifically aforementioned are achieved, and it is to be understood that various modifications of structure might be resorted to without departing from the spirit of the invention as defined by the claims.

Having described my invention, what I claim as new, and desire to secure by Letters Patent is:—

1. As an article of manufacture, a glove drier, including a substantially flat body having an enlargement provided with five finger-like extensions formed about one end thereof and having a centre line disposed symmetrically with respect to said five fingers, said body having a portion extending away from said enlargement in the opposite direction of said fingers, such extension being provided with a plurality of perforations disposed along said centre line, and provided with a slot at the side of the centre line and extending toward the fingers and to the centre line and along the centre line in a direction away from the fingers, thereby forming a shoulder 85 to prevent disengagement from its support.

2. As an article of manufacture, a glove drier, including a substantially flat body having an enlargement provided with five finger-like extensions formed about one end thereof 90

and having a centre line disposed symmetrically with respect to said five fingers, said body having a portion extending away from said enlargement in the opposite direction of said fingers, and provided with a slot commencing at the side of the centre line and extending toward the fingers and to the centre line and along the centre line in a direction away from the fingers thereby forming a shoulder to prevent disengagement from its support.

In testimony whereof I affix my signature.

ROBERT KNOX.
